UNITED STATES PATENT OFFICE.

PERCIVAL J. REEVE, OF HADDONFIELD, NEW JERSEY.

DESIGN FOR A PARASOL-HANDLE ORNAMENT.

45,352.

Specification for Design.

Patented Mar. 3, 1914.

Application filed December 4, 1913. Serial No. 804,775. Term of patent 3½ years.

● *To all whom it may concern:*

Be it known that I, PERCIVAL J. REEVE, a citizen of the United States, and a resident of Haddonfield, Camden county, New Jersey, have invented a new, original, and ornamental Design for a Parasol-Handle Ornament, of which the following is a specification, reference being had to the accompanying drawing, in which the figure illustrated represents a front elevation of the ornament or ornamentation for parasol-handles.

This ornamentation simulates a bunch of

flowers indicated at 1, tied at 2 to the parasol handle 3, which is shown by dotted lines. A loop of cord 4 is also secured by the means securing the flowers to the handle.

I claim:

The ornamental design for a parasol handle ornament, substantially as shown and described.

PERCIVAL J. REEVE.
